(57) **CLAIM**

The ornamental design for a drawer organizer, as shown and described.

DESCRIPTION

FIG. 1 is a front elevation view of a drawer organizer showing the new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a perspective view thereof in which bins of the drawer organizer are arranged side-by-side; and,

FIG. 8 is a perspective view thereof in which four bins of the drawer organizer are stacked inside of a fifth bin of the drawer organizer.
